UNITED STATES PATENT OFFICE.

CHARLES E. THOMAS, OF WILLIAMSTOWN, NEW JERSEY.

CLAMP FOR FRUIT-JAR CAPS, &c.

SPECIFICATION forming part of Letters Patent No. 478,771, dated July 12, 1892.

Application filed February 23, 1892. Serial No. 422,521. (No model.)

To all whom it may concern:

Be it known that I, CHARLES E. THOMAS, a citizen of the United States, residing at Williamstown, in the county of Gloucester and 5 State of New Jersey, have invented certain new and useful Improvements in Clamps for Fruit-Jar Caps, &c.; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to certain new and useful improvements in devices for fastening the covers of fruit-jars and other vessels; and it has for its object to provide a simple and inexpensive device of the character mentioned 20 which may be readily applied to any of the fruit-jars of ordinary construction and which will serve to securely bind and hold the cover in place against the possibility of accidental displacement.

25 The device is equally well adapted for use in securing caps of covers which fit over the upper end or entrance of the jar and also for securing corks and that class of jar-covers which are designed to fit within the entrance 30 of the jar and rest upon an inwardly-projecting flange or shoulder.

To these ends and to such others as the invention may pertain the same consists in the peculiar construction and in the novel combination, arrangement, and adaptation of parts, 35 all as more fully hereinafter described, shown in the accompanying drawings, and then specifically defined in the appended claims.

The invention is clearly illustrated in the 40 accompanying drawings, which, with the letters of reference marked thereon, form a part of this specification, like letters of reference indicating the same parts throughout the several views, and in which drawings—

45 Figure 1 is a perspective view of the device applied to an ordinary fruit-jar. Fig. 2 is a like view of the device as applied to a cork or cover which is fitted within the entrance

to the jar, and Fig. 3 is an enlarged detail in perspective of the clamp removed from the 50 jar. Fig. 4 is a vertical section through the mouth of the jar shown in Fig. 2.

Reference now being had to the details of the drawings by letter, A designates a fruit-jar of ordinary construction, which is provided 55 with the usual annular projection or collar B, which extends around the mouth of the jar, upon the upper face of which collar is placed the rubber packing-ring C, upon which is seated the downward-extending edge of the cap 60 or cover D.

The clamping device E is made, preferably, of sheet metal, and consists of the body portion F, made in a single piece and provided with arms F' F'', which diverge from the point 65 at which their inner ends are united at an angle of substantially fifty degrees. These arms extend to the outer edge of the cap or cover of the jar, and thence down over the collar B, and the extreme ends of the arms 70 are turned inwardly, as shown at f, said inwardly-extended portions being adapted to hook under or engage the lower edge of the collar B, as shown.

The body portion F of the clamp is provided 75 between the arms F' at their point of juncture with an extension F², and to this extension is pivoted the inner end of the arm G, which arm is similar in form to the arms F' just described, and its outer end is adapted, 80 also, when in position to engage the collar B of the jar.

In Fig. 2 of the drawings I have shown the clamp as applied to that form of jar which is provided with a cap or cover which fits within 85 the mouth of the jar and has its outer edges seated upon an inwardly-projecting shoulder or flange H.

Having thus described my invention, what I claim to be new, and desire to secure by Letters Patent, is—

1. A cover-fastener for fruit and other jars, consisting of the body portion F, having radial hooked arms F' and extension F², and the hooked arm G, pivoted at its inner end to the 95 extension F² and its outer hooked end adapt-

ed to engage the lower edge of the collar upon the jar, substantially as described, and for the purpose specified.

2. In combination with a fruit or other jar having an annular collar at its mouth, the cap or cover and the clamping device consisting of a body portion having two hooked arms and a third hooked arm pivotally connected with the body portion, said clamp being adapted to fit over the top of the cap or cover and

the ends of the arms to engage the lower edge of the collar upon the jar, substantially as described, and for the purpose specified.

In testimony whereof I affix my signature in presence of two witnesses.

CHARLES E. THOMAS.
